[57] **CLAIM**

The ornamental design for a safety splash guard for metal working machines, as shown and described.

DESCRIPTION

FIG. 1 is a perspective view of a safety splash guard shield for metal working machines showing my new design;

FIG. 2 is an elevational view thereof as seen from the front in FIG. 1;

FIG. 3 is a side elevational view thereof as seen from the right in FIG. 1;

FIG. 4 is an elevational view thereof as seen from the rear in FIG. 1;

FIG. 5 is a top plan view thereof.
